V. J. BURRY,
SIDE BEARING FOR CARS,
APPLICATION FILED OCT. 24, 1917.

1,344,859.

Patented June 29, 1920.

FIG. 1

FIG. 2

FIG. 3

UNITED STATES PATENT OFFICE.

VINCENT J. BURRY, OF CHICAGO, ILLINOIS, ASSIGNOR TO JOLIET RAILWAY SUPPLY COMPANY, OF CHICAGO, ILLINOIS, A CORPORATION OF ILLINOIS.

SIDE BEARING FOR CARS.

1,344,859.

Specification of Letters Patent. Patented June 29, 1920.

Application filed October 24, 1917. Serial No. 198,255.

To all whom it may concern:

Be it known that I, VINCENT J. BURRY, a citizen of the United States, and resident of Chicago, in the county of Cook and State 5 of Illinois, have invented a new and useful Improvement in Side Bearings for Cars; and I do hereby declare the following to be a full, clear, and exact description thereof.

My invention relates to side bearings for 10 railway cars, and has for one of its principal objects the provision of means whereby the anti-friction member cannot be accidentally disengaged from its bearing housing when it is relieved of the weight of the car body.

15 A further object is to provide a side bearing that will provide for free rolling travel under normal conditions and a sliding travel under abnormal, while, at the same time, certain guiding trunnions of the anti-friction member or roller will be relieved of 20 shearing strains when the limit of rolling movement of the roller is reached.

The construction is such also that should 25 the body bearing move a greater distance than the limit of travel of the rolling member, and thus cause a flat spot on the roller, this would not be objectionable with my construction as it is evident that the roller will not make a complete revolution; therefore, 30 a flat spot at such point on its circumference would never come in contact with the rolling face of said roller housing, and would not affect the normal rolling action of the roller.

35 The invention comprises, broadly, therefore, means for accomplishing these several purposes.

In the accompanying drawings, Figure 1 40 is a sectional view of my improved bearing showing the roller in normal position in full lines, and its limited movement in either direction in dotted lines; Fig. 2 is a plan view of the part shown in Fig. 1; and Fig. 3 is a vertical section on the line 3—3, Fig. 2.

45 In the drawings, 1 indicates a housing having a lower bearing-plate 2, said housing having guides 3 formed on its opposite side walls, which project inwardly from the side walls 4 of the housing. Within this housing 50 is mounted an anti-friction member or roller 5, which is indicated in Figs. 1 and 3, and is of more or less skeleton construction above its center axis, and is of solid construction below said axis so that normally it tends 55 to assume a position with the solid portion

below the axis. This roller, preferably, on each side of the solid portion, is provided with lugs or trunnions 6, which, when the roller is in normal centered position, as shown in Fig. 1, contact with the surfaces 60 of the guide members 3 at the points 7—7. The guide members 3 above these contact points are cut away slightly so that when the roller moves toward either end of the housing 1, the lugs on the side of the roller 65 opposite the direction of movement moves away from the guide members as indicated at the upper dotted-line position of one of these lugs 6, Fig. 1; thus both the guide member and the lugs are relieved of contact, 70 thus permitting the roller to roll free from limited movement to normal position in either direction. The lugs, however, on the side of the roller corresponding to its direction of movement follow down the guiding 75 surfaces of the guide members, remaining in contact therewith whereby the roller is constantly controlled in its rolling movement and is prevented from direct rectilineal shifting movement without rotation. The 80 end walls of the housing are curved as at 8 to conform to the shape of the roller, and are so positioned that the face of the roller contacts with either of these end walls just as the lug 6 reaches the lowermost position 85 of the guide member 3 where the curve of these guide members joins the curve of the end walls 8.

In order to prevent the shearing off of 90 the lugs or trunnions 6 when the roller reaches either limit of its movement, these lugs or trunnions are so positioned that the face of the roller 5 will engage the curved end walls 8 of the housing just as, or slightly before, the lugs 6 reach the lower portion 95 of these curved end walls; therefore, when the roller is at either limit of its rolling movement, further movement thereof is taken up and prevented by the end walls 8, and the lugs 6 are relieved of any holding 100 strain tending to prevent further rolling of the roller.

If the rollers in abnormal condition reach the end walls 8 somewhat before the upper bearing plate 9 has reached the limit of its 105 swiveling or shifting movement, whereupon said upper bearing plate will slide upon the roller 5 during further movement, and if any flattening of the roller should occur by such sliding movement, that will not affect 110

the rolling action of the roller since the roller never makes a complete revolution and, in fact, preferably, does not make a complete semi-revolution.

5 In order to prevent the roller 5 from being accidentally jolted or lifted out of its bearing housing 1, the upper edges of the side walls 4 thereof are provided with overhanging guards or flanges 10 having a space 10 11 between them for the ready insertion of the lugs 6 of the roller into the housing. It will be seen from an inspection of Fig. 1 that at every operative position of the roller within the housing, one pair or both pairs 15 of the trunnions or lugs 6 lie beneath these flanges 10 so that it is impossible for the roller to be jolted or lifted out of the housing during normal use, and it can be only lifted out by turning the roller to a position 20 to bring the lugs of the roller successively in alinement with the opening 11.

From the above-described construction, it will be seen that by a very simple arrangement of the housing and its guides and the 25 roller and its guide lugs, the several objects of the invention above described are accomplished.

The invention is not limited to the details 30 of construction and arrangement of parts herein described, but may be varied to any desired extent within the scope of the appended claims. It is apparent that rockers may be employed instead of rollers, and the term "rollers" is understood to include 35 rockers.

What I claim is:

1. A roller bearing for railway cars comprising a housing, a single roller in said housing, single faced guides at opposite sides

of said housing having converging guide 40 faces, two projections at each end of said roller on opposite sides of said guides and coöperating respectively with said guide faces, and overlying portions extending over said projections when in normal position, 45 and having openings between the same for the insertion of said projections.

2. A roller bearing for railway cars comprising a housing, a single roller contained in said housing, single faced guides at opposite sides of said housing having converging guide faces, two projections at each end of said roller on opposite sides of said guides and coöperating respectively with said guide faces, and inwardly extending 50 flanges adjacent the upper end walls, which extend over said projections when the roller is in normal position, said flanges having an opening formed between the same for the insertion of said projections.

3. A roller bearing for railway cars comprising a housing, a single roller in said housing, guides at opposite sides of said housing having converging guide faces, two projections on said roller at each end on 55 opposite sides of said guides and coöperating respectively with said guide faces, the upper portions of said guides being cut away on both sides whereby one set of said projections will be free from contact with said 60 guides, as said roller rolls on said bearing.

In testimony whereof I, the said VINCENT J. BURRY, have hereunto set my hand.

VINCENT J. BURRY.

Witnesses:

JOHN F. WILL,
J. R. KELLER.
